UNITED STATES PATENT OFFICE

FRANK KEMERER, OF KERSEY, PENNSYLVANIA.

ELECTRIC SWITCH.

1,141,863.

Specification of Letters Patent. Patented June 1, 1915.

Application filed October 3, 1913. Serial No. 734,666.

To all whom it may concern:

Be it known that I, FRANK KEMERER, a citizen of the United States, residing at Kersey, in the county of Elk and State of Pennsylvania, have invented new and useful Improvements in Electric Switches, of which the following is a specification.

The invention relates to an improved switch designed particularly for use with mining turbine pumps wherein the depth of water in the well will automatically govern the running of the pump in order to prevent operation of the latter when the well contains insufficient water for the siphon.

The main object of the present invention is the provision of a switch arranged for such control of the pump as to permit operation of the latter only when sufficient water exists in the well, the failure of the water supply so controlling the switch as a cut out operation of the pump.

The invention in its preferred form of detail will be described in the following specification, reference being had to the accompanying drawings, in which:

Figure 1 is a view in elevation illustrating the improvement in the application thereof, the parts being shown in circuit closing relation. Fig. 2 is a similar view with the parts in circuit opening position. Fig. 3 is a sectional view on the line 3-3 of Fig. 1. Fig. 4 is a plan view of the trolley lever and connected parts.

Referring particularly to the accompanying drawings, the improved device comprises a frame 1 preferably, though not necessarily, rectangular, which is designed to be supported in any preferred way immediately above and adjacent the well 2 from which the pump 3 is designed to draw the drainage water as is usual.

A float rod 5 is mounted for movement vertically of the frame 1, the upper end of said bar being preferably guided in a fixed frame bar 4. The lower end of the float rod carries a float 6 designed to be positioned upon the surface of the water in the well.

Supported between the upper frame bar 5 and the supporting bar 4 is a frame 7 preferably of insulating material longitudinally slotted for a portion of its length, as at 8. Secured to one face of the frame 7 is a plate 9 having a longitudinal recess 10 coincident with the slot 8 in the frame, and in said recess is mounted a replacing block 11, the

upper edge 12 of which inclines downwardly toward what will be termed the rear of the frame. The replacing block is connected to a link 13 with a lever 14 pivoted on the plate, the opposite end of this lever is connected to a push bar 15 guided to an eye 16 secured to the frame and provided at its upper or free end with a semicircular receiving lip 17.

Secured to the side bar of the frame adjacent the upright 7 is an electrical connector 18 from which extends a contact rod 19, the latter being mounted for a vertical swinging movement and for a slight lateral movement, as will be evident. The contact rod 19 forms one terminal of the circuit, which includes a suitable source of energy and also a control mechanism for the pump, all of which parts may be of any usual or preferred construction and need not be shown or specifically described herein. The lower wall of the slot 8 inclines oppositely to the inclination of the replacing block, so that when the rod 19 is freed to drop into said slot it will be automatically guided to the highest point of the replacing block, it being understood that in normal or inoperative position of the parts the upper end of the surface 12 of the replacing block is coincident with the lowest point of the bottom wall of the slot 8. Secured upon a bracket carried by the side and top wall of the main frame is what I term a trolley lever 20, one end of which is connected to the float rod by a removable link 21, and the opposite end of which carries a trolley wheel 22 in electrical connection with the control circuit and forming in effect a terminal of said circuit. Carried by the trolley lever is a pressure arm 23 so positioned that in the downward movement of the trolley lever said arm will engage the receiving lip 17 of the push bar and depress the same to elevate the replacing block. The trolley lever is preferably of insulating material throughout so that the trolley wheel thereof is the only point energized whereby the circuit or the control of the pump is closed through the engagement of the trolley wheel with the rod 19, and broken to stop the pump upon the disengagement of the parts.

In operation it will be obvious that as long as the arm 23 and trolley wheel are connected the circuit will remain closed and the pump operated. As the level of the water in the well is lowered the float de-

scends drawing down the trolley lever until when the predetermined level of the water has been reached, the trolley wheel will be in such elevated position that the 5 arm, which is of the appropriate length, will ride off of said wheel and thus break the connection to stop the pump. As the arm is freed when riding off the wheel it will fall in the slot 8 and reaching the bottom wall 10 of said slot will be deflected to one side, as previously described, so that the free end of the rod is beyond the plane of the trolley wheel. As the level of the water in the well again rises the trolley wheel N of the 15 lever is depressed until the arm thereon rides into the lip of the push bar and on further movement of the lever depresses said push bar with the effect to elevate the replacing block. The upward movement of 20 this block carries the free end of the rod 19 upwardly above the trolley wheel and the inclined surface of the replacing block guides said arm into a position to be engaged by the trolley wheel. The circuit is 25 thus reestablished and the pump started.

This device is entirely automatic and will 30 actively control the pump in accordance with the level of water in the well so that under no conditions will the pump continue 35 operating after the level of the well has fallen below the siphon. The disadvantages of the pump under such conditions will be understood as where the pump is operating simply on air it becomes heated and soon 40 rendered unfit for further use. Aside from the trolley wheel and its connections for the terminal of the circuit, and the rod 19 and its circuit connections all parts are effectively insulated so that under no circumstances can the circuit be closed except in a manner described.

What is claimed is:—

1. A control switch for mining turbine pumps, a frame, a contact rod forming one 25 circuit terminal supported on the frame for

vertical and lateral movement, means for guiding the rod and deflecting it laterally in its vertical movement in one direction, a trolley lever including a contact wheel to engage the rod in the elevation of the lever, 50 said lever being of a length to permit disengagement of the rod from the wheel at a predetermined position of the lever, and means for elevating the rod and restoring it to normal position for engagement by the 55 wheel in its upward movement.

2. A control switch for mining turbine pumps, a frame, a contact rod forming one circuit terminal supported on the frame for 60 vertical and lateral movement, means for guiding the rod and deflecting it laterally in its vertical movement in one direction, a trolley lever including a contact wheel to engage the rod in the elevation of the lever, 65 said lever being of a length to permit disengagement of the rod from the wheel at a predetermined position of the lever, and means to elevate the rod and restore it to normal path to be engaged by the wheel.

3. A control switch for mining turbine 70 pumps, a frame, a contact rod forming one circuit terminal supported on the frame for vertical and lateral movement, means for guiding the rod and deflecting it laterally in its vertical movement in one direction, a 75 trolley lever including a contact wheel to engage the rod in the elevation of the lever, said lever being of a length to permit disengagement of the rod from the wheel at a predetermined position of the lever, a push 80 bar to elevate the rod and laterally deflect the same to restore it to normal position, and means carried by the lever to operate the push bar.

In testimony whereof I affix my signature in presence of two witnesses.

FRANK KEMERER.
